UNITED STATES PATENT OFFICE

THOMAS RALPH SNEYD KYNNERSLEY, OF BOMBAY, INDIA

SAFETY RAZOR

Application filed April 20, 1929, Serial No. 356,665, and in Great Britain May 7, 1928.

This invention relates to safety razors of the general type in which the edge of the guard is at an angle to the edge of the blade with the intention of obtaining an oblique cutting action, and particularly to safety razors of this general type in which the edge of the guard is at right angles to the axis of the handle so that the oblique cutting action is obtained when the razor is drawn over the face in the normal way.

A safety razor according to this invention has a guard plate or table to which the blade is clamped and this guard plate or table is so shaped and so inclined to the axis of the handle that the edge of the guard is at right angles to that axis and the cutting edge of the blade inclined relatively to the guard edge.

The invention is more particularly concerned with safety razors of the well known type in which a thin blade with two cutting edges is clamped between a guard plate or table and a clamping plate, and the following description of an improved razor of that kind is given by way of example.

The guard plate or table is made with two slots parallel to each other and disposed so that when the blade is clamped down upon the plate its cutting edges are parallel with the slots and positioned relatively thereto so that soap and hair may pass through the slots. The blade-supporting portion of the guard plate, instead of being at right angles to the axis of the handle as is usually the case, is inclined thereto, but the guard edges are not parallel with the slots but are at right angles to the axis of the handle.

Thus, in use when the guard edge rests on the face the natural movement of pulling the handle in the direction of its length must result in the desired oblique cutting action.

The invention may be carried out in various ways but it is shown as applied to the known flexible double-edged blade type of razor in the accompanying drawings, in which

Figure 1 is an elevation showing the parts assembled,

Figure 2 is a sectional elevation showing the handle, guard and clamping member separated ready for assembly,

Figure 3 is a plan of the guard plate, and Figure 4 a section on the line 4-4 of Figure 3,

Figure 5 is a plan of the razor blade.

The safety razor illustrated is of the well known type comprising a detachable handle A, a curved guard plate or table B, and a clamping plate C furnished with a screw-threaded stud C¹ to engage the internally screwthreaded socket A¹ in the handle. The guard plate is provided with openings B¹ to receive not only the screwthreaded stud C¹ but projections C² which engage corresponding openings D¹ in the blade D and position this upon the guard plate.

According to the present invention the guard plate is provided with two slots E which are parallel to each other and so arranged that when the blade D is clamped down upon the plate B, its cutting edges are parallel with the slots E and so positioned relatively thereto that soap and hair can pass through the slots.

The main portion of the guard plate B, instead of being at right angles to the axis of the handle as is usually the case, is inclined as clearly shown in Figure 2, but the guard edges E¹ are not parallel with the slots but are at right angles to the axis of the handle i. e., the guard plate, though furnished with parallel slots, has inclined or taper edges E¹ most clearly seen in Figure 3. The exposed portions of the guard are preferably provided with grooves or serrations E² to ensure proper shaving conditions.

Adjacent to the corners on the slots E, i. e. adjacent to the corners of the blade, small projections or raised shoulders E³ are provided to prevent any risk of the corners of the blade scratching or cutting the face and there may also be a slight step or depression in the surface of the guard plate adjacent to the cutting edge. The ends of the clamping plate are also provided for the same purpose with extension lugs or fingers C³ as shown in Figures 1 and 2 which overlap the corners of the blade when it is clamped between the plate and the table in the usual way.

In assembling the parts the screwthreaded shank C¹ and the studs C² on the clamping

plate C are passed through apertures in the blade D and in the guard plate B, whereupon the end of the screwthreaded shank is engaged by the tapped hole A¹ in the upper end 5 of the handle. As clearly shown in Figure 2 the screwthreaded shank is loosely mounted on the clamping plate so that its axis is not at a fixed angle relatively to the plate. The under surface of the guard plate is recessed, 10 as clearly shown in Figure 2, to form a seating for the upper end of the handle, or an inclined boss may be formed on the under surface of the plate B to obtain the same result. This arrangement facilitates the manufacture 15 of the plate in the first instance and enables the plate to be put on either way with relation to the guard table, the stud automatically taking up the correct angular position when the handle is attached and screwed 20 home against the inclined boss or socket.

The invention is equally applicable to razors of the kind in which a hollow cylindrical member, forming the main part of the handle, is integral with the guard plate and furnished 25 with a removable internally screw-threaded portion adapted to engage a screw-threaded pin on the clamping plate.

It will be appreciated that the screw-threaded shank may be mounted on a pin or 30 pivot upon the plate or may be arranged so as to rock within an opening or socket thereon without being detachable therefrom, the particular mounting adopted being capable of 35 variation without departing from the invention.

It is however to be understood that the invention is not necessarily restricted to a razor of the particular type illustrated or even to a double-edged razor, although this arrangement 40 is preferable, as with such a construction either cutting edge will give an oblique cut whichever way the razor is held as clearly illustrated in Figure 3 which shows the converging guard edges in plan.

45 What I claim as my invention and desire to secure by Letters Patent is:—

1. A holder for a safety razor blade including in combination a guard plate, means cooperating with the guard plate to hold a 50 blade in position thereon, a guard edge on said guard plate the guard being shaped so that the guard edge is inclined to the longitudinal axis of the plate and also to the main portion of the plate, a handle and means for fixing said handle to the guard plate so that the main portion of the guard plate is inclined to the axis of the handle and the guard edge is at right angles to the axis of the handle.

60 2. A holder for a safety razor including in combination a guard plate, means cooperating with the guard plate to hold a blade in position thereon, a guard edge on said guard plate the guard being shaped so that the guard 65 edge is inclined to the longitudinal axis of

the plate and also to the main portion of the plate, a slot in the guard plate between the main portion of said guard plate and said guard edge and parallel to the longitudinal axis of said guard plate, a handle, and means for fixing the said handle to said guard plate so that the main portion of the guard plate is inclined to the axis of the handle and the guard edge is at right angles to the axis of the handle. 70

75 3. A safety razor comprising a guard plate, a blade, a clamping plate for clamping said blade on said guard plate, position registering means for said guard plate, said blade and said clamping plate, a guard edge 80 on said guard plate inclined to the cutting edge of the blade and to the main portion of said guard plate, a handle and means for fixing said handle and clamping plate to said guard plate so that the guard plate is 85 inclined to the axis of the handle and the guard edge is at right angles to the axis of the handle.

90 4. A safety razor comprising a guard plate, a blade, a clamping plate, a screw-threaded stud fixed at an angle to said clamping plate, and adapted to engage in a hole in said guard plate and in said blade, position registering means for said guard plate, said blade and said clamping plate, a 95 guard edge on said guard plate inclined to the cutting edge of the blade and to the main portion of the guard plate, and a handle having a screwthreaded socket to receive said stud on said clamping plate. 100

105 5. A safety razor comprising a guard plate, a blade, a clamping plate, a screw-threaded stud fixed at an angle to said clamping plate, and adapted to engage in a hole in said guard plate and in said blade, position registering means for said guard plate, said blade and said clamping plate, a guard edge on said guard plate inclined to the cutting edge of the blade and to the main portion of the guard plate, a slot in 110 the guard plate between said cutting edge and said guard edge parallel to said cutting edge, and a handle having a screwthreaded socket to receive said stud on said clamping plate. 115

120 6. A safety razor comprising a guard plate, a blade, a clamping plate, a screw-threaded stud loosely mounted on said clamping plate and adapted to engage in a hole in said guard plate and in said blade, position registering means for said guard plate, said blade and said clamping plate, a guard edge on said guard plate inclined to the cutting edge of the blade and to the main portion of the guard plate, a handle having a screwthreaded socket to receive said stud on said clamping plate, and means on said guard plate to engage the top of said handle socket so that when the handle is screwed on to the stud 125 130

said stud inclines at an angle to the clamping plate, said guard plate is inclined to the axis of the handle and said guard edge is at right angles to the axis of the handle.

- 5 7. A safety razor comprising a guard plate, a blade, a clamping plate for clamping said blade on said guard plate, position registering means for said guard plate, said blade and said clamping plate, extension 10 lugs on said clamping plate, said lugs overlapping the cutting edge of the blade at its ends a guard edge on said guard plate inclined to the cutting edge of the blade and to the main portion of said guard plate, a 15 handle and means for fixing said handle and clamping plate to said guard plate so that the guard plate is inclined to the axis of the handle and the guard edge is at right angles to the axis of the handle.
- 20 8. A safety razor comprising a guard plate, a double-edged blade, a clamping plate having a central screwthreaded stud inclined to said clamping plate and positioning projections adapted to engage in holes 25 in said guard plate and said blade, guard edges on the guard plate inclined to the cutting edges of the blade and to the main portion of the guard plate, slots in the guard plate between said cutting edges and said 30 guard edges parallel to one another and to said cutting edges and a handle having a screwthreaded socket to receive said central stud on said clamping plate.

In testimony whereof I have signed my
35 name to this specification.

THOMAS RALPH SNEYD KYNERSLEY.
